United States Patent Office

Des. 189,976
Patented Mar. 28, 1961

189,976

RETURN TOP

Wayne E. Lundberg, Milwaukee, Wis., assignor to Donald F. Duncan, Incorporated, Chicago, Ill., a corporation of Delaware

Filed Aug. 13, 1959, Ser. No. 57,166

Term of patent 7 years

(Cl. D34—15)

Fig. 1.

Fig. 2.

I claim:

The ornamental design for a return top, as shown.
